UNITED STATES PATENT OFFICE.

JOHN B. PHELPS, OF BIRMINGHAM, ALABAMA.

NURSING-BOTTLE SUPPORT.

1,110,712.

Specification of Letters Patent. Patented Sept. 15, 1914.

Application filed October 29, 1913. Serial No. 797,957.

To all whom it may concern:

Be it known that I, JOHN B. PHELPS, a citizen of the United States, residing at Birmingham, in the county of Jefferson and State of Alabama, have invented new and useful Improvements in Nursing-Bottle Supports, of which the following is a specification.

This invention relates to bottle holders, 10 has particular reference to a holder for milk bottles for nursing infants, and has for its object to provide a holder which may be placed upon any flat surface, such as on the floor, on a bed or crib, or upon any 15 support upon which the infant rests.

The device is adapted to straddle or extend over the infant and support the bottle at any desired angle above the infant so that the child may lie upon its back and 20 take milk from the bottle without aid.

The invention also aims at the production of a device of this nature which is light in weight, economical to produce since it may be formed of but two lengths of wire, and 25 a device which may be readily adjusted to various heights and angles above the infant to accommodate the device to various conditions met with during use.

Other objects and advantages of this invention will appear from the following detail description of the present and preferred embodiment of this invention illustrated in 30 the accompanying drawing wherein—

Figure 1 is a perspective view of the support. Fig. 2 is an end elevation of the support having a milk bottle applied thereto, the dotted lines showing various adjustments of the device.

Referring to the drawing it will be observed that the support consists of two 40 lengths of wire, preferably inelastic. One length of wire is looped at its middle portion to provide a relatively small bottle neck receiving loop 10 which extends upwardly to substantially a vertical position. The wire adjacent the loop 10 is twisted to provide a forwardly extending arm 11 which extends substantially horizontally from the bottom of the loop 10 a short distance, at 45 which latter point the ends of the wire are bent at right angles and in opposite directions to the arm 11 for a purpose herein-after set forth.

The second length of wire is in a similar 55 manner looped at its middle portion into a relatively large bottle receiving loop 12

which is turned upwardly into parallelism with the loop 10. The wire adjacent the loop 12 is twisted and bent substantially horizontally to provide an arm 13 extending in 60 the line of direction of the arm 11 and forming therewith a cross-arm for supporting the bottle. The ends of the second wire are bent at right angles and in opposite directions from the inner end of the arm 13. The oppositely extending ends of the two wires are twisted about one another to provide a bar 14 of double thickness which supports the cross-arm. The extremities of the two wires are bent down in diverging relation 70 from one another to provide a pair of supporting legs 15 at each end of the bar 14, the legs being preferably looped to provide supporting feet 16 upon the lower ends of the legs. 75

In use the support is placed over the infant and the legs 15 extend down to the floor or support at either side of the infant and hold the bar 14 slightly above the infant. In this manner the weight of the support and the bottle carried thereby is taken up by the legs 15 and the bottle does not rest upon the child as is usual as in the devices heretofore constructed. The bottle 17 is now passed through the loop 12 and the neck of the bottle engaged through the loop 10. Since the support is made up of inelastic wire the cross-arm, made up of the arms 11 and 13, may be bent or twisted about the bar 14 as is desired whereby the bottle 85 will be supported in proper position above the infant. The dotted lines in Fig. 2 show the cross-arm bent down at a rather sharp angle disclosing the wide range of adjustment of which the present device is capable. 90 In Fig. 2 there is also shown in dotted lines the position of the legs 15 when they are bent toward one another whereby the bar 14 is raised up to the desired height from the floor so that the support may be adjusted to 100 prevent the resting of the bottle and the bar on the infant. 95

It is thus seen that the device may be adjusted into very many positions so as to accommodate the support to almost any condition met with; the support is light in weight, and is relatively small, so that it will occupy but little room, and may be easily carried about; and the device is a simple one which may be manufactured 105 economically as it comprises but two strands of wire which are twisted about one another 110

and looped as above disclosed. It is, of course, understood that the device may assume various other designs in the twisting of the wire provided that the essential elements of the device be retained, namely, the bar extending over the infant to support the bottle and the supports or legs extending down at the opposite sides of the infant.

What is claimed is,—

- 10 1. A nursing bottle support comprising a bar, means for supporting said bar, an arm carried across said bar and adapted to be adjusted thereabout into various positions, and bottle engaging means carried upon the ends of said arm.
2. A nursing bottle support comprising a single bar, adjustable legs mounted on the ends of the bar for supporting the same, a cross-arm mounted on the bar and adapted 20 to swing thereabout for adjustment into various horizontal positions, and bottle re-

ceiving loops on the opposite ends of said cross-arm.

3. A nursing bottle support comprising two lengths of wire each of which is looped 25 and twisted for a short distance at its middle portion to receive the opposite ends of a bottle, the free ends of the wires being twisted together in pairs and projecting oppositely and horizontally at right angles to 30 the looped and twisted portions, the extremities of the wires diverging downwardly to provide spaced apart pairs of legs for supporting the device.

In testimony whereof I have hereunto set 35 my hand in presence of two subscribing witnesses.

JOHN B. PHELPS.
